UNITED STATES PATENT OFFICE.

GASTON A. BRONDER, OF BROOKLYN, NEW YORK.

COAL-HOPPER FOR GAS-RETORT CHARGERS.

SPECIFICATION forming part of Letters Patent No. 687,600, dated November 26, 1901.

Application filed September 14, 1900. Serial No. 30,008. (No model.)

To all whom it may concern:

Be it known that I, GASTON A. BRONDER, a citizen of the United States, and a resident of the borough of Brooklyn, in the county of 5 Kings and State of New York, have invented certain new and useful Improvements in Coal-Hoppers, of which the following is a specification.

The object of this invention is the production of a hopper capable of carrying a large quantity of coal which can be easily discharged by means of chutes constituting part of said hopper.

Figure 1 represents a vertical section of my 15 hopper, taken on the line $x x$ of Fig. 3. Fig. 1^a shows a fragmentary section of Fig. 1 on line s . Fig. 1^b shows a fragmentary section of Fig. 1 on line t . Fig. 2 shows an outside elevation. Fig. 3 represents a front view. 20 Fig. 4 is a top view of the hopper. Fig. 5 shows a side elevation of an end sliding bracket. Fig. 6 shows a section of Fig. 5 on line $a' a'$. Fig. 7 represents a side view of one of the middle sliding brackets. Fig. 8 25 is a section of Fig. 7 on line $b' b'$. Fig. 9 shows a fragmentary section through two of the chutes on line $y y$ of Fig. 3. Fig. 10 shows a fragmentary section on line $w w$ of Fig. 9.

The hopper is shown with three outlet-openings (although a greater or less number could be incorporated) and is shown mounted on a truck C of a gas-retort-charging machine. The truck consists of the wheels D D, turning with axles D' D'. Cross-beams G are 35 carried on beams c', which also support the journal-boxes F F F F. In Fig. 1 there are also shown in section the scoops of a retort-charging machine to represent the applicability of my hopper to such an apparatus.

40 The hopper H is secured to the carriage C by means of the legs H' H² H³. The said legs are fastened to the sides of the hopper and abut against the angle-irons H³. The hopper is divided into three compartments h h' h² of 45 approximately equal volumes, which constitute chutes for discharging the contents. These compartments are proportioned to increase in volume downwardly from their throats, avoiding choking the coal. They 50 are formed by the plates p p p, terminating in the curves 17. Plates r r r extend from

the plates p, and both are secured in place by the brackets 3 3 3. Angle-irons v v' to v³, inclusive, strengthen the structure. The compartments are tied at their upper ends 55 with suitable braces 1, 2, and 2^a. The plate m extends from the front wall of the hopper to give the compartment h its proper capacity. The upper ends or mouths of the compartments are side by side, so as to be capable of being simultaneously filled when the hopper is run under a bin. The curves 17 are of large radii to reduce friction and insure an easy discharge and are shaped to also constitute retaining-troughs N N N. The 60 troughs N are formed by the plates n, which extend outward from the plates r and are supported on the brackets 29 and 29^a. They bend down at their outer ends to form the chutes N'. Side clips o' and o³ tie the sides of 65 the hopper and the chutes N'. Under and beyond the curved portion of each chute is located a pusher, which carries the coal from the retaining-troughs N and pushes it toward the chutes N', by which the coal is delivered 70 into scoops when they are in proper position to be charged by the coal-hopper. The pushers, of which there is one for each compartment, consist of the curved cover 4, with the sliding brackets 30 and 30^a, operating under 75 the guides N² and extending between the sides 5 5 of the hopper. On the inside of the curved pushers 4 are fastened the brackets 7, which carry the pins 8 for the links 9. Square cross-shafts O extend between the sides 5 5 80 and are journaled at the ends in the journal-box brackets 10 and 10^a. The journal-box brackets 10 10 are fastened to the sides 5 5 of the hopper, and the brackets 10^a are fastened to angle-irons 23, secured to the sides of the 85 hopper and also carried on the carriage C. Cranks 11 are bolted to the shafts O and are connected to the links 9 by the pins 12. The pins 12 can be placed at different radial distances from the centers of the cross-shafts O 90 by using different holes in the cranks, as 13, so as to be enabled to change the strokes of the pushers and also to obtain different lengths of strokes for the respective ends of each pusher, because it may be desirable for a 100 pusher to have a longer stroke on one end than on the other, the result of which would be

to deliver more coal in one end of the gas-retort-charging-machine scoop than in the other.

In order to insure the discharge of the coal through the throats q q q of the hopper, stirring-bars 14 are linked to the pushers 4 by means of the links 15 and brackets 16. The bars 14 are so placed that their ends 14^a always touch the curved plates 17 of the chutes. 10 From the cross-shafts O swing the levers 20 with handles 26, to which are pinned the handle-bars 21, the said bars being secured by pins 22 to the levers 20, and by means of which through the cranks 11 and links 9 the 15 pushers 4 and stirring-bars 14 are actuated. To the legs H' are fastened the guides 24 and 25 to support the handle-bars at the rear ends.

It will be seen that the lever 20 of the lowest 20 chute takes an upward direction from the cross-shaft O, as it would not be practicable to take a downward direction when used on a carriage C, as here represented.

To use the hopper, it is first run under a 25 coal-bin and filled, when it is moved in operative position for charging retorts, and to make the coal issue from the chutes any one of the handles 26, 27, or 28 is moved.

Having described my invention, I desire to 30 secure by United States Letters Patent, and claim—

1. A hopper containing compartments constituting chutes terminating in curves of large radii, forming the upper and lower walls of 35 said compartments; troughs extending from said chutes; plates extending downward from the chutes; brackets connecting the chutes and extension-plates; brackets connecting the troughs and extension-plates; side clips connecting the outward ends of the troughs with the sides of the hopper.

2. A hopper comprising compartments constituting chutes; troughs connected to the compartments; pushers operating in the 45 troughs; cross-shafts; cranks with ends containing a number of holes to secure different strokes, fastened to cross-shafts; brackets fastened to the pushers; links connecting the

said cranks and brackets; levers secured to the cross-shafts; handle-bars pinned to the 50 levers to actuate the pushers.

3. A hopper; pushers extending between the sides of the hopper, consisting of a plate curved approximately at right angles; sliding brackets supporting the said curved plate; 55 brackets fastened to the plates; links pinned to the brackets; in combination with cross-shafts; cranks fastened to said shafts; links connecting the cranks and the brackets fastened to the pushers; levers fastened to the 60 cross-shafts; handle-bars pinned to the levers.

4. A hopper; troughs in the hopper; pushers operating in said troughs; in combination with stirring-bars; journal-brackets fastened 65 to the pushers; links pinned to the brackets and secured to the stirring-bars.

5. A coal-hopper, curved chutes leading to its delivery-openings, troughs below and extending outward from the chutes, pushers 70 sliding in the troughs, stirring-bars linked to the pushers, the said stirring-bars sliding on the lower ends of the chutes, in combination with a carriage supporting the hopper, legs connecting the hopper with the carriage.

6. A hopper H, comprising compartments h , h' , h^2 , constituting chutes with curved outlets 17, troughs N, and chutes N', cross-shafts O, cranks 11 of variable radii secured to the cross-shafts, pushers with covers 4 operating 80 in the troughs N and under the curved ends 17 of the chutes, brackets 7 connected to the pushers, links 9 connecting the brackets 7 and cranks 11, stirring-bars 14, brackets 16 connected to pushers; links 15 connecting the 85 said brackets and stirring-bars, levers 20, with handles 26 secured to cross-shafts, handle-bars 21 with handles 27 and 28 linked to the levers 20.

Signed at New York, in the county of New 90 York and State of New York, this 11th day of August, A. D. 1900.

GASTON A. BRONDER.
